UNITED STATES PATENT OFFICE.

ALEXANDER McNAB, OF BRIDGEPORT, CONNECTICUT.

REVERSING RUDDER.

Application filed November 22, 1924. Serial No. 751,446.

To all whom it may concern:

Be it known that I, ALEXANDER McNAB, a subject of the King of Great Britain, residing at Bridgeport, Connecticut, have invented certain new and useful Improvements in Reversing Rudders, of which the following is a specification.

The present invention particularly relates to improvements in the rudder set forth in 10 the prior United States Patents Nos. 1,186, 210 and 1,467,521 to which reference is made for any fuller information desired as to the characteristic features thereof. The description of the known features of the rudder in 15 the present application is limited to only such details as are necessary to a clear comprehension of the improvements contemplated by the present invention.

It has been found in actual operation of 20 craft fitted with the rudder that the provision of a really tight closure of the two rudder plates when going astern was difficult to attain owing to mechanical considerations. Even when the abutting edges of 25 the rudder plates had received a careful finishing operation to make a satisfactorily tight joint under normal conditions, the application of power accidentally or through some slight lack of precision in the operating gear, for even a few instants after the 30 plates had come into contact, was liable to cause the meeting edges to be sprung apart, thus permitting water to escape therebetween and lessening the effectiveness of the 35 rudder.

A further point to be considered in forming the rudder was to guard against buckling of the rudder plates when stopping the 40 way of the ship. This necessitated the provision of relatively heavy gauge plates in the form of construction set forth in the prior applications.

The aim of this invention is to provide a 45 construction by which the above described drawbacks of the known construction of the rudders are obviated, a much improved closure of the rudder plates being obtained while the weight of the rudder plates is not increased and in fact may be considerably 50 reduced.

The object of the invention is to provide 55 a rudder of the kind described with corrugations adjacent the meeting edges of the rudder plates, said corrugations being formed to permit the meeting edges to slide slightly

one over the other should said plates be forced toward one another after their meeting edges come into contact.

A further object of the invention is to provide a rudder of the kind described with a 60 plurality of strengthening corrugations spaced from one adjacent the leading edge to one adjacent the trailing edge of the plates.

A further object of the invention is to 65 provide a rudder of the kind described having segmental corrugations extending vertically throughout the length of the rudder plates.

A further object of the invention is to 70 provide a rudder of the kind described with corrugations for the purpose described of such size as to cause no material increase in the skin friction of the rudder.

Further objects of the invention will hereinafter appear and be specifically pointed out in the appended claims.

The invention is illustrated in the accompanying drawings in which—

Fig. 1 is a perspective view of the rudder 80 formed according to the present invention.

Fig. 2 is a plan view of the rudder constructed according to my invention, the rudder plates being shown in closed position in order to reverse the ship or boat.

Fig. 3 is a detail cross sectional view showing the relatively small size of the corrugations.

The Kitchen rudder with the improvement of which the present invention is concerned, consists essentially of two blades 1, 1 each substantially semicircular in vertical section and pivoted together vertically preferably so as to surround the propeller. The blades are so shaped along the rear vertical edge that they may be brought into contact throughout the length of said rear edge, their inner faces then being substantially at right angles and preventing the passage of any water therebetween.

One of the blades or deflectors is operated by a solid shaft "6" and the other by a hollow shaft "7" concentric with the solid shaft. By suitable mechanism the deflectors or rudders are made to turn together in the same 105 direction or equally in opposite directions.

To be as effective as possible the rudder should be placed in, or near, the propeller race. This ensures that the speed of the water passing over the rudder will be greater 110

than the speed of the vessel through the water by a varying value which may be as much as 30 per cent; and that in starting the ship from rest there will be a flow of water over the rudder, giving steering power before the vessel has much weight on. This is effected in the most efficient way possible, since not only are the blades in the propeller race but confine the race adjacent the propeller.

Variation of Speed.—For ordinary direct speed ahead the rudder will be opened until nearly parallel, being slightly less at the after end. When the deflectors are partially closed, the speed of the boat will be reduced to about one-half the full ahead speed, the engines still running at the same revolutions. When the rudders are closed still further the boat will remain stationary. In this case the forward thrust on the propeller is balanced by an equal astern thrust on the rudders. When the deflectors are closed together, the reaction on the rudders causes the vessel to go astern. This position gives the maximum astern speed.

Steering.—The vessel can be steered by carrying helm on the rudders, whether they be fully open, partially closed or quite closed. It has been found that 25 degrees to 30 degrees of helm is quite sufficient for all practical purposes, although with ordinary rudders as much as 38 degrees or even 40 degrees of helm is used. This limitation of helm angle tends to decrease of size in the steering gear. Under these conditions the vessel can be made to turn about on axis somewhere near her middle length without moving ahead or astern.

It will be understood from the description of the arrangement and working of the rudder that it is subjected to very considerable stresses and in order to resist these completely as is necessary to avoid deformation tending to prevent the rudders from closing properly, it has been hitherto necessary to make the rudder plates from relatively heavy metal, this in turn imposing a greater load on the operating gear. Even when the rudder blades are of material sufficiently heavy to prevent buckling or distortion under normal working, it is very easy, particularly when using power rudder control, to damage the rudder by continuing the closing movement of the rudder plates after they have come into contact. This results at least in causing the plates to buckle along their meeting edges, allowing water to escape therebetween.

To both provide a construction of plate which will not be readily damaged in the way described and to reduce their weight, I provide the plates with corrugations extending preferably the full length of the plate, a corrugation extending adjacent or along the meeting edges of the plates. The

free edge of the plate, i. e. between said corrugation along the meeting edges of the plates and the edge of the plates, or the edge of the corrugation itself, is formed as a groove, a segment of a circle concentric with that from which the co-operating corrugation or bend on the co-operating plate is struck. The result of this construction is that not only do the edges of the plates nest securely together without the careful finishing of the meeting edges hitherto necessary, but any accidental application of power after the said meeting edges have come into contact does not cause the plates to spring away from each other along portions of said edges which are enabled to slide for a limited but sufficient amount over one another while maintaining an efficient closure preventing the passage of water between the plates.

In the drawings Fig. 1 shows the rudder mounting and the arrangement of the grooves in the rudder plates 1, 1. Fig. 2 indicates the trailing edge groove in one plate while 3 indicates the corresponding groove in the other rudder plate. In the rudder illustrated the mating joint is formed between the edge of the plate lying beyond the groove 2 and the side of the corrugation 3. As previously described the edge of the plate 2 is bent into a segmental groove concentric with the groove 3 with the result that the edges nest securely together and can work or slide over one another to the slight extent liable to occur in practice without distorting the plates or causing the edges to spring apart.

The grooves 2, 3 act to reinforce the trailing edge of the rudder while the grooves 5 act similarly to strengthen the forward edge of the rudder. Any desired number of corrugations may be formed in the plates intermediate the forward and rear corrugations, in the rudder illustrated a single groove 4 being shown.

The provision of these corrugations has been found to effect important increases in the strength for weight of the rudder, enabling a lighter gauge of sheet metal to be employed while obtaining a more rigid construction.

The functioning of the rudder is also much improved both by the resistance to injury by faulty handling and to the better closure obtained.

It is to be understood that I do not desire to limit myself as to the number or characteristics of the grooves or corrugations provided in the rudder plates. Any form of corrugation, annular, or of various curvatures may be employed provided the desired result is obtained, the most suitable form being determined by consideration of the various factors involved such as gauge of metal or ease of manufacture. The form

described and illustrated in the drawings has been found to give very satisfactory results in actual practice.

I declare that what I claim is—

- 5 1. In a rudder for ships or boats comprising two plates pivoted to be movable from a position of substantial parallelism to a position in which the trailing edges contact with one another, the provision of corrugations adjacent the meeting edges of the rudder plates, said corrugations being formed to permit the meeting edges to slide slightly one over the other should said plates be forced toward one another after their meeting edges have come into contact.
- 10 2. In a rudder for ships or boats comprising two plates pivoted to be movable from a position of substantial parallelism to a position in which the trailing edges contact with one another, the provision of strengthening corrugations spaced from one adjacent the leading edge to one adjacent the trailing edge, the latter corrugations on the two plates being arranged to form a mating joint.
- 15 3. A rudder for ships or boats comprising two plates bent into semicircular form and pivoted together on a vertical axis so as to be movable between a position of substantial

parallelism and a position in which the rear 30 or trailing edges of the plates make a tight joint, provided with vertically arranged corrugations segmental in form.

4. A rudder for ships or boats comprising two plates bent into semicircular form and 35 pivoted together on a vertical axis so as to be movable between a position of substantial parallelism and a position in which the rear or trailing edges of the plates make a tight joint, provided with corrugations arranged to extend from or adjacent one of 40 said pivots to or adjacent the other pivot.

5. In a rudder for ships or boats comprising two plates pivoted to be movable from a position of substantial parallelism into a 45 position in which they contact with one another along one edge, the provision of corrugations of such a depth as to cause no appreciable increase in the skin friction of the rudder, the corrugations at or near the rear 50 edge of the plates forming a mating joint capable of a certain amount of sliding movement over one another while maintaining a tight closure preventing the passage of water between the plates.

In testimony whereof I have affixed my signature.

ALEXANDER McNAB.
